US00D844856S

(12) **United States Design Patent** (10) **Patent No.:** **US D844,856 S**
(45) **Date of Patent:** **** Apr. 2, 2019**

(54) **PAVER**

(71) Applicant: **PAVESTONE, LLC**, Atlanta, GA (US)

(72) Inventor: **William H. Karau**, Southlake, TX (US)

(73) Assignee: **PAVESTONE, LLC**, Atlanta, GA (US)

(**) Term: **15 Years**

(21) Appl. No.: **29/609,697**

(22) Filed: **Jul. 4, 2017**

Related U.S. Application Data

(62) Division of application No. 29/543,176, filed on Oct. 21, 2015, now Pat. No. Des. 791,346.

(57) **CLAIM**

The ornamental design for a paver, as shown and described.

DESCRIPTION

FIG. 1 shows a perspective view of a paver according to the present disclosure;

FIG. 2 shows a top view of the paver illustrated in FIG. 1; FIG. 3 shows a bottom view of the paver illustrated in FIG. 1;

FIG. 4 shows a right side view of the paver illustrated in FIG. 1;

FIG. 5 shows a left side view of the paver illustrated in FIG. 1;

FIG. 6 shows a front view of the paver illustrated in FIG. 1; and,

FIG. 7 shows a rear view of the paver illustrated in FIG. 1. The broken lines shown in the figures form part of the boundary of the claimed paver and are not part of the claimed ornamental design.

1 Claim, 5 Drawing Sheets
